CORD EQUALIZING MECHANISM FOR
VENETIAN BLINDS

Max J. Stogran, Chicago, Ill.

Application October 24, 1949, Serial No. 123,257

6 Claims. (Cl. 160—176)

1

My invention relates to the conventional type of tilt mechanism for Venetian blinds, and more particularly to means incorporated in such a mechanism for facilitating the equalizing of the tilt cords.

One object of the present invention is to provide a mechanism for the purpose mentioned which facilitates the equalizing action without imposing wear on the tilt gearing.

A further object is to design an equalizing mechanism which is confined to the tilt rail gear and extremely compact.

Another object is to construct an equalizing mechanism which is entirely automatic in operation and which utilizes the tension in the folding of the blind to restore the tilting facility to the same after the tilt cords have been equalized.

An important object is to employ a minimum number of parts in the construction of the equalizer, so that it may add but slightly to the cost of the tilt gearing.

With the above objects in view, and any others which may suggest themselves from the description to follow, a better understanding of the invention may be had by reference to the accompanying drawing, in which—

Fig. 1 is an elevation of a typical tilt gearing installation in a fragment of a Venetian blind;

Fig. 2 is an enlarged section on the line 2—2 of Fig. 1;

Fig. 3 is a section on the line 3—3 of Fig. 2;

Fig. 4 is a view similar to Fig. 2, showing the portion of the equalizing mechanism at one end of the tilt gearing travel; and

Fig. 5 is a view similar to Fig. 4 showing the portion of the equalizing mechanism at the other end of the tilt gearing travel.

In accordance with the foregoing, specific reference to the drawing indicates the head rail of the Venetian blind at 10, the tilt rail at 11, the ladder tapes at 12, the slats at 13, the tilt cords at 14 and 15, and the guides for the same at 16. The tilt gearing is composed of a hanger 20, a spindle 21 journaled in the same and carrying a worm 22 and tilt cord pulley 23, and a gear-sector 24 in mesh with the worm 22 during the tilting operations. The worm gear is extended with a bracket 25 having a receptacle 26 for the spindle 21 of the tilt rail 11. Thus, when the slats 13 are level—as indicated in Fig. 1—the position of the gear-sector bracket 25 is lowermost and also level, as seen in Fig. 2; and a down pull on the tilt cord 14 or 15 serves

2

to operate the worm gearing and tilt the blind accordingly.

Repeated actuation of a tilt cord as mentioned induces a slight slippage of the cord over the pulley 23, so that in time the affected cord becomes considerably longer than its companion, and presents an unbalanced appearance. For this reason, one mechanism or another has been devised to permit the cords to be threaded back freely over the pulley until they depend at substantially equal length, this process being termed as the equalizing of the cords.

In the novel embodiment, the equalizing mechanism resides in the assembly of the gear-sector 24 with the hanger 20. Thus, the latter is perforated to receive a rivet 30 formed with a square head 31 on the rear side of the hanger. On the frontal side the rivet is enlarged with a circular stud 32; and the latter is enlarged with a circular plate 33.

The gear-sector 24 is formed with an elliptical opening 35, one of whose sides is constricted to a pointed edge 36 at the middle, so that such side forms a pair of adjoining pockets 37; and each of these is of a capacity to seat the stud 32, as shown in Figs. 4 and 5. The edge of the plate 33 contains a substantially semi-circular notch or depression 40 at the top. The gear-sector 24 is stamped from the rear to project a pair of small circular studs 42 in forward direction, these being a short distance from the bracket 25 and on opposite sides of the circular plate 33; and the gear-sector has its final teeth 44 continued as cams 45 which are inclined to meet the side edges of the bracket.

It is evident from Fig. 2 that when the blind is open—with its slats in the horizontal position shown—the gear-sector rests with the undivided side of its opening 35 on the stud 32; and the ends of the opening are spaced equally from the stud by virtue of the studs 42, which serve as bearings in relation to the periphery of the frontal plate 33.

When the gear-sector is in the position just described it is in full mesh with the worm 22. Therefore, the rotation of the latter in either direction accomplishes the tilting of the blind accordingly. Ordinarily, the slats 13 close in over-lapping sequence at the end of the tilting travel in either direction; and they are in substantially vertical position when closed. However, when it is desired to equalize the tilt cords 14 and 15, the shorter one of these should not only be pulled down to accomplish the closing 55 of the blind as just stated but pulled slightly

lower. If this operation rotates the gear-sector in the counterclockwise direction from the position of Fig. 2, it is apparent from Fig. 4 that the extra downpull of the shorter cord has rotated the gear-sector to a point where its bracket 5 has passed the vertical position to the left as shown. This action brings the right hand stud 42 of Fig. 2 to a topmost position; and the weight of the blind plus the clearance now afforded by the gear-sector opening 35 pull down 10 on the gear-sector with the effect of seating the upper stud 42 in the notch 40 and lowering the gear-sector out of mesh with the worm 22. Presumably, the downpull on the shorter cord may now be continued without affecting the 15 blind, until both cords hang at equal length.

When the equalizing of the cords 14 and 15 has been accomplished as stated, it follows that the blind should be reopened to the level or tilted position, as desired. According to the position of the parts in Fig. 4 this is not possible, as the gear-sector 24 and the worm 22 are out of mesh. However, since the blind has been tilted beyond the end of its closing travel, and a wrapping pull imposed on its tapes 12, the tendency of these is to unwrap and urge the blind to rotate in the returning direction. This action is reflected in the urge upon the upper final tooth 44 and cam 45 to rotate in the clockwise direction. This urge has a lifting effect 20 on the tooth 44, so that the latter trips the threads of the worm 22 as the same rotates on the downpull of the shorter cord section. However, if the other cord is pulled—after the cords 25 have been equalized—and the worm rotated in the opposite direction, the final gear-sector tooth 44 receives a positive urge in the clockwise direction by the foremost worm thread, this causing the gear-sector to lift the stud 42 out of the notch 40. The stud now resumes its travel 30 as a bearing to maintain the gear-sector centered on the stud 32 and therefore in mesh with the worm, so that the untilting or opening feed of the blind follows.

It is now seen that one pocket 37 of the gear-sector opening served as a clearance to permit the upper gear-sector stud 42 to fall into the notch 40. Fig. 5 shows the position of the parts when the other cord is the shorter one and is pulled as described to equalize the cords. The other stud 42 and pocket 37 now come into play, and the action is duplicated.

It is now apparent that the novel equalizing mechanism is actuated merely by the normal downpull of the shorter tilt cord to close the blind with final tension, this action automatically releasing the cord pulley for free rotation to quickly equalize the cords. The equalizing mechanism is fully contained in the installation of the worm gearing, so that nothing projects therefrom to form an obstruction or complicate the tilt gearing. Further, the chambered construction of the gear-sector facilitates the quick and certain drop of the gear-sector to clear the worm for free rotation. Further, the studs 42 not only serve to cooperate with the notch 40 for the gear-sector dropping function, but serve at all other times as bearings to maintain the gear-sector in centered position. Finally, the parts entering the equalizing mechanism are few and quite simple, enabling the mechanism to be produced at low cost.

While I have described the invention along specific lines, various minor changes or refinements may be made therein without departing

from its principle, and I reserve the right to employ all such changes and refinements as may come within the scope and spirit of the appended claims.

I claim:

1. A tilt cord equalizing mechanism for Venetian blinds comprising a support, a spindle journaled in the latter and carrying a worm, a pulley at one end of the spindle over which the tilt cords are trained, a stud projecting forwardly from the support at a point below the worm, and a gear-sector normally in mesh with the worm and adapted to be connected in supporting relation to one end of the blind tilt rail, said gear-sector having an internal opening for journaling the gear-sector on said stud for rotation in either direction to control said tilt rail accordingly, said opening being elongated in a direction to create a clearance over the stud when the gear-sector has been rotated by the actuation of the shorter tilt cord to a point closing the blind with a slight subsequent tension, and said clearance permitting the gear-sector to drop a sufficient distance in such event to clear its teeth from the worm and permit the pulley to turn freely as said cord is drawn to a level even with its companion cord.

2. A tilt cord equalizing mechanism for Venetian blinds comprising a support, a spindle journaled in the latter and carrying a worm, a pulley at one end of the spindle over which the tilt cords are trained, a stud projecting forwardly from the support at a point below the worm, and a gear-sector normally in mesh with the worm and adapted to be connected in supporting relation to one end of the blind tilt rail, said gear-sector having an internal opening for centrally journaling the gear-sector on said stud for rotation in either direction to control said tilt rail accordingly, said opening being elongated in both directions from the center to create a clearance over the stud when the gear-sector has been rotated by the actuation of the shorter tilt cord to a point closing the blind in either direction with a slight subsequent tension, and said clearance permitting the gear-sector to drop a sufficient distance in such event to clear its teeth from the worm and permit the pulley to turn freely as said cord is drawn to a level even with its companion cord.

3. The structure of claim 2, and means maintaining the gear-sector in centered position during the rotation period before said point.

4. The structure of claim 2, a frontal circular enlargement for said stud, and a pair of secondary studs carried by the gear-sector on opposite sides of said enlargement, said secondary studs serving as bearings for the gear-sector around the periphery of the enlargement during the rotation period of the gear-sector before said point to maintain the gear-sector in centered position during such rotation.

5. The structure of claim 2, a frontal circular enlargement for said stud, and a pair of secondary studs carried by the gear-sector on opposite sides of said enlargement, said secondary studs serving as bearings for the gear-sector around the periphery of the enlargement during the rotation period of the gear-sector before said point to maintain the gear-sector in centered position during such rotation, and the positions of the secondary studs being such as to locate one or the other above the enlargement when the rotation of the gear-sector reaches said point in the corresponding direction, and

the top of the enlargement having a recess as a clearance to receive the stud over the enlargement in the event of said drop.

6. The structure of claim 1, the last gear-sector tooth in said rotation terminating with a decline and tripping the threads of the worm on the free rotation of the pulley and the tendency of the gear-sector to reverse its rotation due to said tension, and such tension also urging the rise of the gear-sector and the meshing of 10 said tooth into the worm thread on the reverse rotation of the pulley to re-open the blind.
